UNITED STATES PATENT OFFICE

2,525,048

SUPPORT FOR BATHROOM CURTAINS

Bertram Siff, New York, N. Y.

Application April 27, 1948, Serial No. 23,525

2 Claims. (Cl. 160—126)

1

This invention relates to new and useful improvements in supports for bath room curtains, or the like, and it has for its object to provide means whereby said curtains will screen the bath tube at all times and thus facilitate a person's entry into and out of a bath tub without at the same time exposing the bath room floor to a spray of water.

Another object of my invention is to provide a device for the above purpose which is inexpensive to manufacture and which may be easily detached when, for instance, a tenant moves from an apartment, as it will furnish no integral part of the appurtenances of a building.

The device consists of a couple or more bars hinged together and a pair of overlapping curtains, as will be hereinafter further described.

If snapfasteners are used for attaching bath room curtains to my devised curtain rods, the female parts of said snapfasteners may be furnished with said rods for those who prefer to make their own curtains.

It is to be understood that my device may be made of any suitable material, such as metal, plastic or a combination thereof.

With the above and other objects in view, this invention consists of the novel features of construction, combination and arrangement of parts, hereinafter fully described, claimed and illustrated in the accompanying drawings forming part of this application, and in which similar characters of reference indicate corresponding parts in all views, and in which:

Figure 1 is a top plan view of my device.

Figure 2 is a front elevational view of same, with curtains attached, and showing my device connected to the conventional curtain rod.

Figure 3 is a top plan view of Figure 4.

Figure 4 is an elevational view showing a modification of my device with parts broken off.

Figure 5 is a section taken on the line 5—5 in Figure 2; while

Figure 6 is a detail elevational view showing a hinge joint of my invention, and

Figure 7 is an elevational view showing as a modification a telescopic feature.

Referring more particularly to the drawing, the numeral 10 indicates the conventional bath room curtain support.

A substantially rectangular main bar 11 is provided with a hinge 14 about centrally thereof, so that it may be easily taken down and collapsed in case of removal by a tenant, or house-cleaning.

Means, for instance, as shown herein, metal

2

straps 15 and 16 are secured to the bar 11 in order to detachably connect said bar to the conventional support 10, as one strap 15 enters into an eyelet 17 in the other strap 16 and is next bent upon itself, as may be seen in Figure 5.

Two rectangular side bars 12 and 13 are arranged one upon each side of the main bar 11 and rigidly secured to the latter by short rods 18.

A plurality of members 19 bent upon themselves into a substantially rectangular shape are adapted to slide on the rectangular bars 12 and 13; said members 19 are, however, upon their inner sides formed with a central open space 21 to permit them to slide over the short rods 18; roller bearings 26 are mounted at the top and bottom of the members 19 to facilitate the movement of the latter on the side bars 12 and 13.

Snap fasteners 20, or the like, are secured to the members 19 and adapted to connect the bath room curtains to the latter; the male parts 30 of said fasteners 20 are secured to the members 19 and the female parts 31 to the curtains.

It will be apparent from Figure 2 that the bars 12 and 13 overlap each other, upon each side of the main bar 11, thus also permitting the bath room curtains 28 and 28' hung on said bars to overlap each other accordingly.

In Figures 3 and 4 have been shown a modification to the effect that if my device is to be used where the stationary curtain support has a bend or curvature, my device is formed with correspondingly shaped dove-tailed end portions as shown at 22 and 32, in Figure 4, while a rod 24 is inserted vertically through a hole 23 in said dove-tailed parts.

Stop brackets 35 are arranged at each end of the rods 12 and 13 to restrict the movements of the rollers 19.

In Figure 7 is shown means for elongating the main rod 11, which is hollow.

Said means consists of a bar 34 slidably disposed within the bar 11, as suitable arrangements, or changes are made, if necessary, to obtain such telescoping operation.

It is obvious that changes may be made in the form, construction and arrangement of the several parts, as shown, within the scope of the appended claims, without departing from the spirit of the invention, and I do not, therefore, wish to limit myself to the exact construction shown and described herein.

What I claim as new, and desire to secure by Letters Patent of the United States, is:

1. Device for the support and manipulation of bath room curtains comprising, in combination,

a rod, a substantially rectangular bar, metal straps detachably connecting said bar to the rod, two rectangular side members overlapping each other and being arranged one upon each side of said bar, short rods rigidly securing said members to the latter, a plurality of slideable members adapted for the support of bath room curtains, said latter members being of a substantially rectangular shape and being formed with a central opening upon one side thereof, whereby to permit said members to slide by said rods.

2. A device, as claimed in claim 1, and wherein said bar is provided with a hinge upon its lower surface for collapsing the bar. 15
